UNITED STATES PATENT OFFICE.

GARDNER B. GRAY, OF PITTSBURGH, PENNSYLVANIA, ASSIGNOR, BY MESNE ASSIGNMENTS, TO AUTOMATIC TRAIN CONTROL & SIGNAL COMPANY, OF PITTSBURGH, PENNSYLVANIA, A CORPORATION OF DELAWARE.

POLARIZED RELAY.

1,140,729.

Specification of Letter Patent.

Patented May 25, 1915.

Application filed September 1, 1911. Serial No. 347,377.

To all whom it may concern:

Be it known that I, GARDNER B. GRAY, a citizen of the United States, residing at Pittsburgh, in the county of Allegheny and State of Pennsylvania, have invented a new and useful Polarized Relay, of which the following is a specification.

The present invention relates to improvements in polarized relays, the primary object of the invention being the provision of a novel form of relay of this character which is especially adapted for use in connection with the train control and signal system as shown in applicant's former U. S. Patent No. 909,083, granted to him January 5, 1909, this particular relay being constructed to control two signal circuits, as for instance a "caution" and a "danger" circuit.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings—Figure 1 is a detailed side elevation of the polarized relay, a portion of the armature being shown in section to show the joint or pivot at that connection. Fig. 2 is a bottom plan view thereof. Fig. 3 is a section line taken on line 6—6 of Fig. 2.

Referring to the drawings, the numeral 7 designates the supporting bracket or casting, which is insulated from a supporting plate (not shown) by means of the strip 7' of insulation, this casting having attached thereto the permanent open-ring magnet 8 in whose lower end is mounted the casing 9, while attached to and depending from its upper end as clearly shown in Fig. 1, is the electromagnet 83. This casing 9 is provided with a socket 9' and with a removable plate 9'' for the reception of the pintle supporting means 10 to which is pivoted the circular end 11 of the oscillatory armature or lever 12 which is disposed as a continuation of magnet 8 and in such a position as to be controlled by the electromagnet 83. The electro-magnet 83 comprises the two

spaced and parallel coils, as shown in Fig. 2, 55 between which extends the armature 12 and which through the medium of the permanent magnet 8 is a polarized relay, the said armature or lever 12 is held normally centrally, but is moved from one side to the other, due to the attraction or force exerted by the electromagnet 83. Carried upon the outer extreme end of the lever or armature 12 is a ball or sphere 13 of insulation, and depending from the forward portion of the 60 casting 7 is a post 14, to whose lower end is attached a plate or frame 15 in whose lugs is rotatably mounted a screw 16 having the milled nut 17 for adjustably carrying the block 18, whose lugs 19 are provided with 65 aligned bores for the reception of the insulation bushing 20, and adjusting screw 21 upon one side and the adjusting screw 22 upon the other side, a terminal plate 20' being disposed between the head of the screw 70 21 and the outer face of the bushing 20, the purpose of which will appear later.

The screws 21 and 22 respectively, are provided with the reduced contact points *b* and *b'*, respectively, which are normally in 80 the path of and are adapted to be contacted by the respective contact points *c* and *c'* carried by the armature or lever 12 in the path of or in the line of the said points *b* and *b'*, respectively. The armature 12 preferably provides a circuit breaker in certain 85 circuits, not shown, and may be connected in said circuit in any suitable manner to open and close the same through the contacts *b* and *b'*.

Connected to the outer face of the frame 15 by means of a plate 23 is a block 24 of insulation which has depending from the underside thereof, the two terminal posts 25 and 25', having attached thereto the two 90 curved spring contacts 26 and 27, respectively, upon whose curved ends as at 26' and 27' respectively are carried the contact plates or washers 26'—27' adapted to be normally in the path of and to engage the 100 inner ends of the blocks 28 and 29 of carbon, said blocks 28 and 29 being adjustably mounted in the terminal posts 30 and 31 respectively, carried upon the underside of the block 24 of insulating material. The spring 105 plates 26 and 27 are preferably made of spring steel, whereas the washers 26' and 27' are made of platinum, thus producing

a durable contact to resist the burning out at the point of contact with the carbon 28 and 29, respectively.

Regarding the contact points 26'-27'-28-29 as shown in Fig. 2, the platinum contact point 26' is made to engage the carbon point 28, and the same way platinum point 27' engages carbon point 29, and the points 28 and 29 are so adjusted that when the polarized relay forces the lever arm against the spring and platinum point 26', a circuit including 26 and 28 is established and another circuit is ruptured at 27 and 29. Likewise when the lever is thrown by the polarized relay in the opposite direction, it opens the contact points 26' and 28, and closes the points 27' and 29. This controls outside circuits directly in accordance with the polarization of the polarized magnets, which are under control of another circuit.

The armature 12 is permanently polarized by the magnet 8 and is adapted to be moved in contact with either of the pole pieces *d* or *e* by the reversing of the polarity of the relay 83. The armature 12 closes the magnetic circuit between the magnet 8 and the pole pieces *d* or *e* of the relay 83 as well as the electric circuit through the armature 12 and either of the contacts *b* or *b'*. Also, the movement of the armature 12 closes and opens electric circuits between the contacts 26' and 28, and between the contacts 27' and 29 by having its insulated head 13 alternately pressing the spring contacts 26 and 27 into and out of electrical engagement with their respective contact points. By this means two signals, such as a "caution" and "danger" signal are controlled by this polarized relay.

It will thus be seen that by constructing the polarized relay according to the details herein set forth, a very simple and efficient construction is produced and one wherein the slightest variation of the respective circuits controlling or controlled thereby, will have the effect or be effected as desired, and that the circuit making or retaining electromagnets will in turn control or be controlled by the said polarized relay or electromagnets.

What is claimed is:

1. A relay, having a bracket, an open ring permanent magnet depending therefrom, two coils and two cores connected to one pole of said permanent magnet, core

plates carried by each core and extending toward each other in spaced relation, an armature pivoted for horizontal oscillation in the other end of the permanent magnet 60 and having its free end projected between the core plates to be influenced thereby, a post depending from the bracket upon the opposite side to the coil from the pivotal point of the armature, means disposed in 65 the lower end thereof for limiting the oscillatory movement of the armature, a block of insulation connected to said post, a plurality of terminal posts carried by said block of insulation and disposed upon opposite sides of the extreme end of the armature, a rod mounted in the extreme end of the armature, a block of insulation carried upon the extreme end of said rod, two oppositely disposed spring contact plates carried by two of said posts and disposed one 70 upon each side of the block of insulation carried by the rod of the armature, and adjustable contacts one to each contact spring carried by the remaining terminal posts, for 75 coaction with the respective spring contacts on the oscillation of the armature.

2. A switch comprising: a permanent magnet, an electro-magnet comprising two coils connected to one pole of said permanent magnet, pole pieces on the opposite end of said magnets, an armature pivoted for oscillation in the other end of the permanent magnet and having its free end extending between the pole pieces of the electro-magnet 85 so as to be influenced thereby, a terminal connected to the armature, contact points arranged in spaced relation on either side of the pivoted armature whereby a circuit may be established through said contacts and the armature, two sets of second contact points insulated from each other, one set on either side of the armature, and an insulated portion on the armature to engage with certain of said second contact 90 points whereby the contact points of each set may be brought into contact with each other to establish a circuit independent of the circuit established through the armature by the movement thereof.

In testimony that I claim the foregoing as my own, I have hereto affixed my signature in the presence of two witnesses.
